Blackhawk Mfg. Co., Milwaukee, Wis., a cor-
poration of Wisconsin

Application December 10, 1938, Serial No. 81,702

Term of patent 7 years

To all whom it may concern:

Be it known that I, Edward M. Pfauser, a citizen of the United States, residing at Elm Grove, in the county of Waukesha and State of Wisconsin, have invented a new, original, and ornamental Design for a V-Base for Metal Straightening Equipment, of which the following is a description, reference being had to the accompanying drawing, forming part thereof.

In the drawing:

Fig. 1 is a perspective view of a V-base for metal straightening equipment, embodying my new design;

Fig. 2 is a top view of the V-base; and

Fig. 3 is a bottom view of the V-base.

I claim:

The ornamental design for a V-base for metal straightening equipment, substantially as shown.

EDWARD M. PFAUSER.
